DISPENSER FOR FLUENT MATERIAL

Cleophas McVicker, Cincinnati, Ohio, assignor
to Kutol Products Company, Norwood, Ohio, a
corporation of Ohio

Application May 4, 1938, Serial No. 206,007

5 Claims. (Cl. 221—108)

This invention relates to a device for dispensing charges of fluent material and is of particular usefulness in the dispensing of powdered soap and like materials.

5 An object of the invention is to provide a device of this kind which obviates leakage and consequent waste of the material.

Another object is to provide a dispenser in which a sufficient charge of the dispensable material is released by a single movement of the actuating member.

Another object is the elimination, in a device of this kind, of spring and similar means which ordinarily become clogged and ineffective after a period of use.

Another object is the provision of such a dispenser in which the parts are simple and readily assembled and taken apart.

These and other objects are attained by the means described herein and illustrated in the accompanying drawing, in which:

Fig. 1 is a front elevational view of the dispenser of this invention.

Fig. 2 is a cross-sectional view taken on line 2—2 of Fig. 1.

Fig. 3 is a cross-sectional view taken on line 3—3 of Fig. 2.

Fig. 4 is a bottom plan view of the dispenser.

Fig. 5 is a cross-sectional view on the line 5—5 of Fig. 3.

With reference to the drawing:

The device comprises a container 8 which may be cylindrical as shown, and which, at the bottom, is preferably tapered, such as by the use of the downwardly tapered sections 9 and 10 forming the lower portions of the container. The top of the container may be closed by a suitable cover 11 and the body of the container provided with a pair of attachment brackets 12 for fastening the device to a wall or suitable support.

40 The lowermost section 10 of the container, which is removable from the section 9, is provided with a bottom 13 provided with a dispensing aperture 14 (Figs. 3, 4 and 5).

45 The edge portion of the bottom 13, adjacent the aperture 14, is built up and formed, as indicated at 15 (Fig. 3), to provide an arcuate ledge 16 (Fig. 5) terminating in a pair of abutments 17 and 18.

50 A dispensing member or wheel 19 is rotatably mounted in the container section 10, on the bottom 13. The wheel is supported centrally upon the inner end of an actuator 20. This end of the actuator is formed to provide a primary shoulder 21 contacting the outer face of the bottom 13, a

secondary shoulder 22 projecting through a perforation 23 in the bottom of the container and having the dispensing member or wheel 19 resting thereagainst and a squared portion 24 projecting into a similarly formed recess 25 in the bottom face of the dispensing member 19. The latter is formed with an upstanding hub 26 and this hub, as well as the inner end of the actuator 20, as seen in Fig. 3, is perforated for receiving a screw bolt 27 adapted to receive nuts 28 on the inner end thereof for holding the various movable parts together.

The dispensing wheel 19 is formed, as shown herein, with radial arms 29. It will be seen in Fig. 5 that recessed portions 30 and 31 between three of said arms 29 are adapted to cooperate with the dispensing aperture 14 of the bottom 13, these recessed portions each being of substantially the same size and shape as the dispensing aperture. As seen in Fig. 5, the actuator 20 has been turned toward the front of the container into contact with a stop 32 provided on the bottom of the container, the stop being so positioned as to limit movement of the dispensing wheel to a position wherein the recessed portion 31 thereof is in substantial registration with the dispensing aperture 14. A similar stop 33 is provided toward the rear of the bottom 13 and is adapted to stop the actuator 20 in such position that the other of the recessed dispensing portions, namely, the recessed portion 30, will register with the dispensing aperture 14 when the actuator 20 has been moved to the position seen in dotted lines.

A baffle plate 34 is positioned in the container portion 10 above the dispensing aperture 14 and is of such size and shape, as seen particularly in Fig. 2, as to cover the two adjacent arms 29 of the dispensing wheel. The baffle plate has its outer edge resting upon the ledge 16 and its inner edge resting upon the hub portion 35 of the dispensing wheel. A washer 36 disposed beneath the nuts 28 on the bolt 27, projects outwardly so as to bear against the baffle plate and hold it in position. The abutments 17 and 18 at the ends of the arcuate ledge prevent lateral movement of the baffle plate.

The distance between the bottom 13 and the baffle plate 34 is substantially equal to the thickness of the arms 29 of the dispensing wheel so that said arms are received snugly therebetween, and inasmuch as the ends of the arms extend into close adjacency with the built-up portion 15 of the bottom of the container, as seen in Fig. 3, leakage of the dispensed material through the aperture 14 is substantially precluded.

55

It will be obvious that when one of the recessed portions 30 or 31 of the dispensing member is in dispensing or registering relation with the aperture 14, the other recessed portion is disposed 5 clear of the baffle plate 34 for receiving a charge of the fluent material which, upon movement of the actuator 20 in the opposite direction, is carried to and dispensed through said aperture. The arms of the dispensing member, other than those 10 which actually carry the dispensable material to release position, are useful in functioning as agitators to preclude caking and solidifying of the fluent material at the bottom of the container.

For repair and replacement of parts, the bottom 15 section 10 of the container is simply removed from operative position in which it may be held by means of screw bolts 37 (Fig. 1) and thereafter the bolt 27, uniting the structural details of the bottom of the container, is withdrawn for dis- 20 associating the parts.

What is claimed is:

1. A dispenser for fluent material and comprising a container formed with a bottom provided with a relatively small outlet aperture, a baffle plate positioned in the container above and in spaced and aligned relation with said outlet, said plate conforming substantially with the outline of said outlet, a dispensing member mounted in the container for reciprocation on said bottom, 25 said dispensing member comprising three arms receivable between said plate and outlet and defining a pair of recesses each of substantially the same outline as said outlet, an operating handle connected to the dispensing member and operable 30 exteriorly of the container, and means limiting operation of said handle to a back and forth movement, said handle and dispensing member being connected in such relation that movement of the handle to its respective limits carries one 35 of said recesses into full registry with said outlet beneath the baffle plate for dispensing a charge 40 of material while the other of said recesses is carried clear of said plate to receive a full charge of material.

2. A dispenser for fluent material and comprising a container formed with a bottom provided with a relatively small outlet aperture, a baffle plate positioned in the container above and in spaced and aligned relation with said outlet, said plate conforming substantially with the outline of 45 said outlet, a dispensing member mounted in the container for reciprocation on said bottom, said dispensing member comprising three arms receivable between said plate and outlet and defining a pair of recesses each of substantially the same 50 outline as said outlet, an operating handle connected to the dispensing member and operable exteriorly of the container, means limiting opera- 55

tion of said handle to a back and forth movement, said handle and dispensing member being connected in such relation that movement of the handle to its respective limits carries one of said recesses into full registry with said outlet beneath 5 the baffle plate for dispensing a charge of material while the other of said recesses is carried clear of said plate to receive a full charge of material, and means on the non-dispensing portions of the dispensing member for agitating the material in 10 the container.

3. A dispenser for powdered and like materials and comprising a cylindrical container formed with a bottom provided with an outlet aperture, a ledge formed in the container along the outer edge of said outlet, a dispensing member rotatably mounted in the container on said bottom and comprising a pair of arms forming a recess for receiving dispensable material, said arms being of such length as to pass said ledge in close 20 adjacency therewith to obviate leakage of said material between said parts, a baffle plate in the container above said outlet and providing for passage of said arms therebeneath, and means for moving the dispensing member from the exterior 25 of the container.

4. In a dispenser for powdered and like materials, the combination of a container formed with a bottom having an outlet therein, a ledge formed in the container along the outer edge of the outlet, a dispensing member rotatably mounted in the container on said bottom and comprising a pair of arms forming a recess for receiving dispensable material, said arms being of such length as to pass said ledge in close adjacency therewith 30 to avoid leakage of said material between said parts, and means for rotating the dispensing member from the exterior of the container.

5. A dispenser for powdered or like materials and comprising a container formed with a bottom 40 provided with an outlet, a ledge formed in the container along the outer edge portion only of said outlet, a dispensing member rotatably mounted in the container on said bottom and comprising a pair of arms forming a recess for receiving 45 dispensable material, said arms, upon movement of the dispensing member, passing said ledge in close adjacency therewith to avoid leakage of material between said parts, said dispensing member being otherwise spaced from the lateral 50 portions of the container to obviate frictional contact during operation of the dispensing member, a baffle plate in the container above said outlet and positioned to provide for passage of said arms therebeneath, and means for operating the dispensing member from the exterior of the container.
